UNITED STATES PATENT OFFICE.

ROBERT ROSTRON, OF CHICAGO, ILLINOIS, ASSIGNOR TO CRERAR, ADAMS & CO., OF CHICAGO, ILLINOIS, A CORPORATION OF ILLINOIS.

BONDING DRILL.

Application filed January 26, 1924, Serial No. 688,643. Renewed November 9, 1928.

This invention relates to track drills and the like and has for its object the production of a track drill of light weight, sturdy and durable construction, and which may be readily adjusted to meet all requirements of service without the need of wrenches or other tools and without possibility of the parts accidentally moving from adjusted relation.

Another important object of the invention is the provision of means for protecting a drill bit in the drill against damage when the drill is not in use.

Numerous other objects and advantages of the invention will be apparent as the same is better understood from the following description, which, taken with the drawings, discloses a preferred embodiment of said invention.

Referring to the drawings:

Figure 1 is a side elevation of a rail drill embodying my present invention;

Fig. 2 is an end view thereof;

Fig. 3 is a detail view of the part of the drill clamp which engages the housing members; and

Fig. 4 is a section taken substantially on the line 4—4 of Fig. 3.

For the purpose of illustrating my present invention I have shown on the drawings a preferred embodiment of it. Reference character 11 represents a combined main housing and post casting. Reference character 12 is the main housing part of this member and with a bottom plate 13 constitutes the drill or transmission housing. It may be stated that gearing is provided within this housing to advance the drill bit and to give to it different speeds as may be desired. This gearing is not shown upon the drawing since it forms no part of the present invention. A rotating spindle 14 is driven thereby and extends forwardly out of the housing and carries a bit socket or sleeve 15 in which is mounted the drill bit 16. Reference character 17 indicates an upwardly extending post carrying a handle 18 and a shaft socket or bearing 19. A shaft 21 is fixed in this socket or bearing and on this shaft is mounted a sprocket wheel 22. A crank arm 23 is fixed with the sprocket wheel 22 and a sprocket chain 24 connects the sprocket wheel with the gearing within the housing.

The housing part 12, post part 17, the socket or bearing 19, and the handle 18 are all preferably of a single casting. Webs or

ribs 25, 26, 27, etc., and openings 28, 29, etc., are provided to produce a light, sturdy construction.

The drill is adapted to be clamped to the rail 31 by two jaws 32 and 33. One of these jaws, 33, is carried by a plate 34 adapted to be fixed in adjusted relation upon a forward plate member 35 of the casting 11, as will be presently described. The other jaw 32 is integral with an arm 36 pivoted upon a stud 37 extending forwardly from the top of the plate 34, a nut 38 holding the arm to the stud. A second and longer stud 39 extends out from the plate 34 and just above the jaws 32 and 33. This stud passes through an enlargement 40 or jaw body 41 and a spring 42 is interposed between this body and the plate 34. A hand lever 43 is mounted upon the stud 39 and has cam surfaces engaging similar surfaces on the body 41, these companion surfaces being indicated by reference character 44. A thumb or wing nut 45 is engaged with the stud 39 beyond the lever 43.

The clamp is operated by adjusting the jaws, when they are free of the rail, through manipulation of the nut 45 so they fit nicely and merely freely over the rail part and then after thus positioned the lever 43 is moved to tightly engage the jaws therewith. This lever when manipulated to clamping position is frictionally held in place because of the pressure exerted on the cam faces and because there is considerable roughness in the surfaces comprising these cam faces. Obviously the lever may be clampingly held in this position by the operator if desired.

The plate 34 is adjustable vertically with respect to plate 35 and to this end is provided with parallel vertically disposed guides 34' adapted to engage shouldered portions 35' of the plate 35 whereby to insure true vertical movement of the plate 34 up and down on plate 35. In addition, I have provided an adjustable engaging means between plates 34 and 35 to hold said plates in various positions of adjustment. This positive engagement consists in the present instance of teeth or serrations 47 and 48 on the engaging faces respectively of the plate members. Two bolts 49 are threaded into the plate 35 and extend through slots 51 in the plate 34. Wing nuts 52 are or may be provided upon the ends of the bolts to be turned down by hand to hold the teeth or serrations in firm engagement after adjustment. The teeth 47 and 48 are

preferably so constructed that when engaged they do not prevent full contact between the bearing surfaces between the two plates.

It will be manifest that both adjustment 5 to proper clamping relation between the jaws and adjustment of the jaws above the bit may be readily accomplished without the use of a wrench or other tool of any kind.

In order that the bit 16 may not be damaged when the drill is not in service, through 10 a tendency of the apparatus to tilt to the left viewing Fig. 1, I provide a protector arranged to co-operate with the housing to support the drill bit free of contact with the supporting surface. In the present instance this 15 protector consists of two legs 55 extending down upon opposite sides of the bit and formed integral with the casting 11.

It is thought that the invention and many 20 of its attendant advantages will be understood from the foregoing description, and it will be apparent that various changes may be made in the form, construction and arrangement of the parts without departing from 25 the spirit and scope of the invention, or sacrificing all of its material advantages, the form hereinbefore described being merely a preferred embodiment thereof.

I claim:

30 1. An apparatus for drilling rails comprising a drill frame, a drill rotatably mounted thereon, said drill frame having an upstanding face provided with serrations, a plate having corresponding serrations adapted adjustably to engage said frame, clamping means 35 for holding said plate in adjusted position on said frame, a clamping jaw carried by the lower portion of said plate, a stud projecting outwardly from the upper end of said plate, 40 a clamping arm carried by said stud, a lower stud projecting outwardly from the lower portion of said plate and passing through a

bore in said clamping jaw, a spring surrounding said lower stud and disposed between said clamping jaw and said plate, said second 45 clamping jaw having a cam surface thereon, a lever on said lower stud provided with a cam surface adapted to cooperate with the cam surface on said clamping jaw, and an adjusting nut on said lower stud adapted to 50 form a rigid backing for said lever.

2. In an apparatus for drilling rails the combination of a drill frame, a rotatable drill carried thereby, said drill frame having a substantially vertical faces provided with vertical, spaced apart shoulders forming guideways and a series of spaced apart teeth disposed intermediate said shoulders, and a plate having vertical guideways adapted to fit in said shoulders, said plate having corresponding teeth adapted to adjustably engage the teeth of said frame, said plate also having vertical slots on either side of said teeth, threaded bolts passing through said slots and into said frame, wing nuts adapted to engage 60 said bolts to clamp said plate in adjusted position on said frame, the top of said plate having an outstanding stud and the bottom of said plate having an outstanding bolt and an outstanding clamping jaw, an arm mounted 70 on said upper bolt and depending therefrom in spaced relation from said plate, the lower portion of said arm having a complementary clamping jaw and a perforated hub portion, said hub portion engaging said lower 75 bolt and having on its rear face a cam wall, a lever mounted on said bolt to provide it with a complementary cam face, an adjustable nut threaded on the end of said bolt to provide a rigid backing for said lever, and 80 a coil spring surrounding said bolt and disposed between said plate and said hub portion of said clamping arm.

ROBERT ROSTRON.
